CLAIM

The ornamental design for a wooden baking pan organizer as shown and described.

DESCRIPTION

FIG. 1 is a front, top, and right perspective view of a wooden baking pan organizer showing my new design;

FIG. 2 is a front elevational view thereof;

FIG. 3 is a rear elevational view thereof;

FIG. 4 is an enlarged left side elevational view thereof;

FIG. 5 is an enlarged right side elevational view thereof;

FIG. 6 is a top plan view thereof;

FIG. 7 is a bottom plan view thereof; and,

FIG. 8 is a perspective view of its use state.
